(57) **CLAIM**

The ornamental design for a divot tool, as shown and described.

DESCRIPTION

FIG. 1 is a front perspective view of an embodiment of a divot tool;

FIG. 2 is a front view of the embodiment of the divot tool of FIG. 1;

FIG. 3 is a rear view of the embodiment of the divot tool of FIG. 1;

FIG. 4 is a right side view of the embodiment of the divot tool of FIG. 1;

FIG. 5 is a left side view of the embodiment of the divot tool of FIG. 1;

FIG. 6 is a top view of the embodiment of the divot tool of FIG. 1; and,

FIG. 7 is a bottom view of the embodiment of the divot tool of FIG. 1.

The broken lines shown in the figures illustrate portions of the divot tool that form no part of the claimed design. The broken line circle in FIG. 3 is a graphic line only and forms no part of the claimed design. The drawings include surface shading that represents contour and not surface ornamentation.

1 Claim, 5 Drawing Sheets
